UNITED STATES PATENT OFFICE

WILLIAM FLEISCHER, OF CAMDEN, NEW JERSEY, AND PETER DI BLASO, OF PHILADELPHIA, PENNSYLVANIA

CLOTH CUTTER

Application filed October 22, 1928. Serial No. 314,058.

Our invention relates to new and useful improvements in a cloth cutter and has for one of its objects to improve the general construction of such devices to produce a compact and 5 strong although light structure.

Another object of the invention is to produce a cloth cutter or more particularly a combined guide and guard from suitable material, such as metal with all the parts fastened into a unitary structure.

A further object of the invention is to so construct a device of the kind mentioned as to produce an enlarged guide portion, a portion of which in connection with a reduced section 10 acts as a guard for a circular knife or cutter.

A still further object of the invention is to form slots in opposite walls of the guard for the reception of the thread by which buttons 20 are sewn to garments or other articles whereby said thread may be cut for the removal of the buttons with the same knife or cutter that is used for severing the cloth.

While we will describe the invention in connection with its use as a cloth cutter, it is to be particularly understood that the same is applicable to other cutting machines used in operations on other substances, such as paper and sheet rubber.

It is quite common for guards of this kind to be placed over cutting wheels with the lower edge spaced from a table or cloth supporting surface whereby the cloth may be passed underneath of it for engagement with the cutter, but we have found that in cutting garments having bodies which are closed lengthwise as well as the sleeves of such garments, it is difficult to keep them opened up or extended during the coacting operations, thus making 30 said operations slower than necessary and sometimes producing bias and uneven edges.

The present invention contemplates overcoming the foregoing difficulties and we have therefore provided a relatively large guide 40 over which the garments may be pulled and which will therefore cause said garments to be spread out, extended or opened up prior to coming in contact with the cutter.

With these ends in view, this invention consists in the details of construction and coin-

bination of elements hereinafter set forth and then specifically designated by the claims.

In order that those skilled in the art to which this invention appertains may understand how to make and use the same, we will 55 describe its construction in detail, referring by numerals to the accompanying drawings forming a part of this application, in which:—

Fig. 1, is a longitudinal sectional view of a 60 cloth cutter constructed in accordance with our invention, a portion thereof being left in elevation to more clearly illustrate details of construction and showing the combined guide and guard associated with a circular 65 cutter or disc knife and a supporting surface which may be the top of a table.

Fig. 2, is a top plan view of the combined guard and guide per se.

Fig. 3, is a section at the line 3—3 of Fig. 2. 70

Fig. 4, is a section at the line 4—4 of Fig. 2.

Fig. 5 is a section at the line 5—5 of Fig. 2.

In carrying out our invention as herein embodied, the combined guide and guard is represented as a whole by the reference character 75 6 and this is produced from suitable material, such as metal preferably aluminum, as a unitary structure including a base plate 7, which is reduced in thickness to provide an extension 8 extending from the inner end of the 80 upper portion of the base plate so that when the device is mounted upon a support 9, such as the top of a table with the base plate resting on the upper or supporting surface, the extension 8 will be spaced from said support 85 surface.

Above the extension 8 extends the circular guard 10 of such size and width as to provide a chamber 11 into which projects a portion of a circular knife or disc cutter 12, said circular 90 knife being mounted in any suitable manner beneath the support 9 and extending through an aperture 13 in said support.

From the rear portion of the guard 10 projects a guide 14 of any desirable cross section 95 configuration and tapering toward its outer or free end and the base of said guide is preferably the same width as the extension 8 so that their surfaces blend into each other.

As will be obvious by reference to Figs. 2 100

and 5, the guide 14 is considerably larger than the guard 10 so that articles, such as wearing apparel, when slipped over the guide will be opened up, extended or straightened out prior to being brought into contact with the circular knife.

By reference to Fig. 2, it will be obvious that the flat portion 15 is like an extension of the top of the guard and by referring to Fig. 1, it will be readily noted that the under face of the guide coincides with the bottom surface of the extension 8, and therefore said extension being spaced from the supporting surface, the guide is also so spaced, thus providing a passageway for the goods to reach the circular cutter.

In the side walls of the guard toward the front thereof are formed two slots 16 and 17, each of which has beveled edges 18 and one of these slots, as 16, is preferably larger or beveled to a greater extent than the other. These slots are of a length sufficient to pass the edge of the circular collar in order that a thread by which a button is sewn to an article may be passed into the slots and brought into contact with the knife for cutting said thread and by making one of the slots, as 17, smaller than the other, the goods to which the buttons is sewn will not be drawn into the space receiving the cutter but the slot 16 being larger, the eye or the convex portion of a button may be readily accommodated.

The rear edge of the base plate is preferably beveled in opposite directions from the center as indicated at 19 to assist in clearing the space between the guard, supporting surface and cutter of pieces of thread, lint or other material that might otherwise accumulate.

The extension 8 and the lower surface of the guide 14 are positioned relative to the under surface of the base plate 7 so that when the device is mounted, the space between the guide, guard and supporting surface is large enough to receive the goods to be cut but so small as to prevent the insertion of an operator's finger thereinto, thereby positively protecting the operator from injury due to carelessness or forgetfulness.

The operation of the device is as follows:—

A person standing in front of the device which is at the left hand side of the illustration in Fig. 1 places the material under the free end of the guide, and moves it in the direction of the arrow "a" and where said material is of general tubular formation, as the sleeves of garments, said material is pulled up over the guide until the portion entering the passageway between the supporting surface and said guide comes in contact with the circular knife or cutter revolving in the direction of the arrow "b". During this operation, the guide will cause the material to be opened up or extended so

that the part entering the passageway will follow a straight line toward the cutter.

Where the material to be cut is a garment or other article having buttons or like fastenings thereon, these are first removed by entering the thread between the fastener and the article to which it is sewn in the slots 16 and 17 until brought in contact with the cutter and by always placing the buttons at one side of the device, said buttons may be permitted to fall into a suitable receptacle.

Of course we do not wish to be limited to the exact details of construction as herein shown, as these may be varied within the limits of the appended claims without departing from the spirit of our invention.

Having thus fully described our invention, what we claim as new and useful is:—

1. A device of the kind mentioned comprising an integral structure including a base, a hollow guard projecting from the rear end of said plate with the lower edge of said guard spaced above the under surface of the base, said guard adapted to enclose a portion of a cutting instrument and a guide projecting from the rear end of the guard with its lower surface in the same plane as the lower edge of the guard while the upper surfaces of said guard and guide blend into each other from which point the upper surface of said guard is inclined downwardly toward its outer end and the cross sectional area of the guide being considerably greater than that of the guard.

2. The structure set forth in claim 1 wherein the guard has a pair of parallel slots in opposite walls for guiding the attaching threads which secure fastening devices to articles into the cutter.

3. A device of the kind disclosed comprising a base plate, an extension projecting from the rear end of said base plate of less thickness than the base plate with their upper surfaces in the same plane thereby producing an off-set between the extension and base plate, said off-set portion being tapered from its transverse center, a hollow circular guard open at its lower end and projecting above the extension and of relatively less width than said extension, said guard adapted to partially enclose a circular cutter, said guard having parallel slots formed in opposite walls thereof and projecting inwardly from the periphery and a guide projecting from the rear ends of the guard and extension and of the same width as the latter with the lower surface of said guide in the same horizontal plane as the lower surface of the extension while the upper surface of said guide is inclined from its outer end toward and blends with the upper surface of the guard for the purpose stated.

4. The structure set forth in claim 3 wherein slots in the guard are provided with

beveled edges to permit the positioning of the articles being operated upon in close proximity to the inner surfaces of the guard.

In testimony whereof, we have hereunto
5 affixed our signatures.

WILLIAM FLEISCHER.
